UNITED STATES PATENT OFFICE.

DEVANEY CLAUDE EDWARD TRAINOR, OF TORONTO, ONTARIO, CANADA, ASSIGNOR OF ONE-THIRD TO JAMES AITKEN MACKERROW AND ONE-THIRD TO HENRY CLAYDON, BOTH OF TORONTO, ONTARIO, CANADA.

AUTOMOBILE CONTROL MECHANISM.

1,386,213.

Specification of Letters Patent.

Patented Aug. 2, 1921.

Application filed August 16, 1919. Serial No. 318,058.

To all whom it may concern:

Be it known that I, DEVANEY CLAUDE EDWARD TRAINOR, a subject of the King of Great Britain, and resident of 119 Huron 5 street, in the city of Toronto, county of York, Province of Ontario, Dominion of Canada, have invented certain new and useful Improvements in Automobile Control Mechanism, of which the following is a 10 specification.

The invention relates to improvements in automobile control mechanism as described in the present specification and shown in the accompanying drawings that form a 15 part of the same.

The invention consists essentially of the novel construction of the hand lever adapted to operate the controller shaft and in the novel means for locking said lever.

20 The objects of the invention are to provide a form of control lever particularly adapted for Ford cars, which may be located centrally of the car, thus permitting of easy access to the car by either side door, to provide an efficient means of locking said hand lever, and generally to provide a form of automobile control mechanism which will be inexpensive of construction, simple of operation, durable and efficient.

25 In the drawings, Figure 1 is a perspective view of a portion of a car with the flooring broken away to disclose the parts located therebelow.

Fig. 2 is a vertical sectional view through 35 the ball located at the top of the hand lever, said view being taken substantially on the line A—A of Fig. 3.

Fig. 3 is a plan view of the lever top with a portion of said top broken away.

40 Fig. 4 is a cross section through the controller shaft taken on the line B—B of Fig. 5 with one half of the adjustable collar shown in dotted lines extended.

Fig. 5 is a detail of one end of the hand 45 lever showing the manner in which same is secured to the controller shaft.

Like numerals of reference indicate corresponding parts in the various figures.

Referring to the drawings, 1 represents 50 the frame of the car on which is supported the flooring 2 through which project the foot levers 3 as customary.

4 is the controller shaft transversely ar-

ranged and mounted in bearings in brackets 5 secured on the under side of the frame 1. 55

6 are links, rigidly secured over the outer ends of the controller shaft 4, and projecting at right angles thereto and having pivotally secured to the ends thereof the brake rods 7. 60

8 is a hand lever projecting through a slot 9 located substantially centrally of the car floor, said lever being provided at its lower end just beneath said floor with a pair of outwardly and downwardly radiating arms 65 10 adapted to encircle the top side of the crank case 11 and to be secured to the controller shaft for the purpose of operating same.

The ends of the arms 10 may be rigidly 70 secured to the controller shaft in any desired manner but in the drawings said arms are shown as each having an enlarged portion 12 shaped to form the top half of a collar and having a portion 13 hinged 75 thereto as at 14 and forming the lower half of said collar, said collars being adapted to be secured around said controller shaft by means of bolts 15 securing together the flanges 16 of each of said collars. 80

The inner walls of the collars are provided with notches 17 forming teeth 18 adapted to engage the controller shaft and thus effectually prevent said collars from slipping. 85

19 is a sector located within the slot 9 in the flooring and extending through a slot 20 in the enlarged lower end of the hand lever 8 and being provided with right angle ends 21 adapted to be secured to the under 90 side of said flooring, said sector being provided on its lower edge with teeth 22.

23 is a pawl arm slidably mounted in a longitudinal slot 24 in the hand lever 8 and being provided at its lower end with a sliding pawl mechanism 25 located within the enlarged lower end of said lever and normally engaging the teeth 22 of the sector 19. 95

The pawl arm projects upwardly into the enlarged and preferably ball shaped top end 100 26 of the lever arm 8 and is provided with an enlarged top portion or plunger 27 adapted to slide within an opening 28 in said ball, said opening being somewhat longer than said plunger and being adapted 105 to accommodate a spring 29 located between

the lower end of said opening and the lower end of said plunger for the purpose of holding said pawl arm normally to its uppermost position and thus hold the pawl firmly 5 in engagement with the teeth 22 of the sector 19.

It will be apparent from the foregoing that so long as the pawl engages the teeth of the sector the hand lever will be held 10 firmly to its position and thus prevents rotation of the controller shaft and to permit of operating said hand lever it is simply necessary to push downwardly on the top end of the pawl arm and thus release the 15 pawl from the sector. Upon release of pressure on the pawl arm the spring 29 will of course force the pawl arm upwardly and cause the pawl to again engage the sector 19.

30 is a plate sliding in a horizontal slot 20 substantially centrally of the ball 26, said plate being slightly greater in length than the thickness of said ball so as to provide a projecting portion or handle 32 and being provided with a slot 33 therethrough 25 through which the plunger end 27 of the pawl arm operates, said slot being slightly longer than the thickness of said pawl arm and being cut away at one end to form a square portion 34 adapted to be inserted in 30 a slot 35 in the plunger 27 when it is desired to lock the pawl arm to its uppermost position.

36 is an opening through one end of the plate 30 for the insertion of a padlock 37 35 for the purpose of locking said plate within the slot 35 in the plunger 27.

38 is a spring operating in a horizontal groove 39 in the roof of the transverse slot through the head and being secured at one 40 end to the outer wall of said groove and at its other end being secured to the plate 30 adjacent to the squared end of the slot 33 and being adapted to hold said plate normally out of engagement with the slot 35 45 in the plunger 27.

In the operation of this invention when it is desired to adjust the brake rods 7 it is simply necessary to press downwardly on the top end 27 of the pawl arm 23 which

disengages the pawl from the sector 19 and 50 permits of said hand lever being reciprocated to rotate the controller shaft. When it is desired to lock the hand lever to any desired position it is only necessary to allow the pawl arm to be forced upwardly to its 55 uppermost limit by means of the spring 29 and then to insert the plate 30 in the slot 35 in the plunger 27 by simply pressing inwardly on the projecting portion 32 of said plate which forces the opposite end of 60 said plate out from the opposite side of the ball 26 and permits of a padlock being secured in the opening 36 and thus effectually preventing said plate from being disengaged from the slot in the plunger. Upon 65 the removal of the lock 37 the spring 38 immediately forces the plate 30 from the slot in the plunger 27 and permits of free usage of said hand lever.

By the use of this invention free access 70 may be had to the interior of the car by either side door as the hand lever is located centrally of the car in place of at one side as in Ford car construction. It will also be seen that the various parts are so 75 inclosed that when the device is locked it is absolutely impossible to operate the hand lever except by removing the padlock, thus effectually preventing theft of the car.

What I claim is:

In automobile control mechanism, the combination with a controller shaft shaped to extend around the lower side of a crank case, of a pair of arms having enlarged lower ends and hinged portions forming 85 clamps adapted to grip said controller shaft on opposite sides of said crank case, said arms being shaped to extend around the top side of said crank case, a hand lever rigidly connected to the upper ends of said arms, 90 and a sector.

Signed at the city of Toronto, Province of Ontario, this 27th day of June, 1919.

DEVANEY CLAUDE EDWARD TRAINOR.
